UNITED STATES PATENT OFFICE

FRANK M. STEINER, OF MINNEAPOLIS, MINNESOTA, ASSIGNOR TO STEINER SALES COMPANY, OF SALT LAKE CITY, UTAH, A CORPORATION OF UTAH

TOWEL CABINET

Application filed January 13, 1927. Serial No. 160,965.

In filling or loading a towel cabinet, it has been customary to wind the loose end on a stick or roll designated as the take-up roll so that in the operation of using the clean 5 towel the soiled web will be synchronously wound on the take-up roll as the clean web is unrolled from the clean roll and when the clean web is exhausted the attendant will remove the stick from the soiled roll returning 10 the soiled roll to the laundry and replacing the stick in the cabinet, the loose end of the fresh clean web placed in the cabinet being wrapped a few times around the stick to repeat the winding operation as the web is used.

15 The object of my present invention is to dispense with this stick or take-up roll and in place thereof provide means whereby the loose end of the used web will be rolled upon itself to form the roll of soiled towel so that 20 when the attendant reloads the cabinet it is only necessary to lift out the roll of soiled towel without the necessity of detaching it from the stick or take-up roll and thus I am able to dispense with one roll or stick which 25 heretofore has been regarded necessary in the construction of the cabinet and save time usually required for filling a cabinet by eliminating the operation of removing the stick from the soiled roll and starting the winding 30 of the fresh roll on the stick.

A further object is to provide a simple inexpensive construction which, without adding materially to the cost of the cabinet, will allow the user of the clean towel to wind 35 up the soiled web as fast as the clean web is used.

Other objects of the invention will appear from the following detailed description.

40 In the accompanying drawing forming a part of this specification,

Figure 1 is a vertical sectional view through a floor cabinet embodying my invention showing the beginning of the formation of the soiled towel roll;

45 Figure 2 is a similar view of the upper portion of the cabinet showing the soiled roll when the clean web is nearly exhausted;

Figure 3 is a sectional view on the line 3—3 50 of Figure 2;

55 Figure 4 is a vertical sectional view show-

ing a modified construction of the means for rolling the soiled web into a roll;

Figure 5 is a vertical sectional view showing the soiled roll practically completed; and 55 Figure 6 is a sectional view on the line 6—6 of Figure 5.

In the drawing, 2 represents the side walls of the cabinet; 3, the front wall having an opening 4 in the upper portion thereof through which the user may have access to the clean towel web; 5, the top of the cabinet, and 6, a mirror preferably arranged at a suitable angle to be conveniently used by a person standing in front of the cabinet.

60 In the lower portion of the cabinet is a chamber 7 having an opening 8 in the rear wall and above this opening is a back plate 9 which substantially closes the rear of the cabinet and forms a guide on which the clean web of towel may slide. 10 is a roll of clean towel 65 that is placed in the chamber 7 and is allowed to roll back and forth therein to unwind the clean web of towel from the roll. From this roll the web is stretched through the opening 8 and up the rear wall 9 over a feed roll 11 70 having a roughened, preferably sanded, surface on which the web of towel will not slip so that when the user grasps the web of towel and pulls thereon the feed roll will be re- 75 volved. A stop device 12 is provided in connection with the feed roll 11 having a key 13 80 that is manipulated by the user of the towel to release the feed roll preparatory to pulling the web of towel. This stop device I make no claim to in this application. 85

When the user grasps the web of clean towel he will draw it outwardly through the opening 4 to a point where the web can be conveniently used and when the user releases the web, it will fall back by gravity within 90 the chamber of the cabinet and depend from the feed roll as indicated by full lines in Figure 1. The end of the web of towel will depend loosely within the cabinet and I provide a trough-shaped support 14 at the lower portion of the cabinet whereon the loose end of the web falls and the bottom of this trough or support is provided preferably with a series of openings 15. A shaft 16 is provided 95 below the openings 15 having a driving con- 100

nection 17 with the feed roll 11 and on this shaft 16 I provide a series of rolls 18 having roughened surfaces preferably by sanding with a portion of the roll projecting upwardly through the openings 15 in the support 14 as shown plainly in Figure 1. These rolls are so positioned with respect to the support 14 that the loose end of the web of towel depending from the feed roll will contact with the surface of these rolls and when the towel is placed in the cabinet the movement of the rolls will slide the loose end of the web to the full line position indicated in Figure 1 and when the extreme end has been pushed to a predetermined point it will tip inwardly by gravity and form the first or inner fold as indicated by dotted lines, a portion of the web contacting with the surfaces of the roughened rolls so that the continued movement of the rolls will cause the web to be folded or rolled upon itself as it lies on the support to form a roll of soiled towel with the convolutions thereof lying closely together as indicated in Figure 2. I am therefore able to dispense with the stick or take-up roll and avoid the necessity of separating the soiled towel roll therefrom when the web of clean towel is exhausted and the cabinet is refilled and thereby save time in filling the cabinet. In Figures 4 and 5 I have shown a modified construction in which I have provided two shafts 19 and 20 driven from the feed roll 11 in the same manner as described with reference to Figure 3, these shafts being each provided with a series of small rolls 21 and 22, provided with roughened surfaces instead of one shaft with a series of larger rolls thereon as shown in Figure 1. I prefer also in this modified construction to provide larger openings 23 in the bottom of the support and through these openings the rolls 21 and 22 project so that the web of soiled towel will contact with both of the groups of rolls, the rolls revolving in the same direction and operating to wind the soiled towel into a roll as it rests upon the support when fed thereto by the action of the user standing in front of the cabinet. The method of winding the soiled web where two sets of rolls are employed is shown in Figure 4 and is substantially the same as described with reference to the previous figures. These winding rolls may be made of any suitable size and there may be any number of them.

I have shown and described this invention as applied to the floor type of cabinet; that is, one having legs and adapted to rest upon the floor of the restroom or other place where the cabinet may be located. I do not, however, confine myself to such use as the invention is applicable to a wall type of cabinet if it is desired to use it in such a structure; that is, a cabinet that is fastened on the wall or other support instead of resting upon the floor.

I claim as my invention:

1. A towel cabinet having means to support a supply of clean towel therein, a feed roll over which a web of clean towel may be stretched for delivery to the user, a trough having a concave inner surface and also having openings therein and whereto the loose end of the towel web is delivered to lie thereon and means geared to said feed roll and operating through said trough and engaging the web of towel to move it on said concave surface and wind it into a roll. 70

2. A towel cabinet having means to support a supply of clean towel therein, a feed roll over which a web of clean towel may be stretched for delivery to the user, a stationary trough having a concave inner surface and also having openings therein and whereto the loose end of the towel web may be delivered to lie thereon, and a roll geared to said feed roll and having a roughened surface operating through said openings in said trough and engaging the loose end of the towel web to wind it into a roll. 80

3. A towel cabinet having means to support a supply of clean towel therein, a feed roll over which a web of clean towel may be stretched for delivery to the user, a winding roll having a driving connection with said feed roll for synchronous operation, a stationary receiver having an upwardly projecting concave portion cooperating with said winding roll to wind the loose end of the towel upon itself to form a roll. 90

4. A towel cabinet having means to support a roll of clean towel therein, a feed roll over which a web of clean towel may be stretched and passed to the user, a trough shaped member having a concave overhanging side, said member having a series of openings in its bottom and winding rolls having a driving connection with said feed roll and operating through the openings in said trough shaped member and engageable with a web of towel to cause it to move up under said overhanging side and wind it into a roll. 100

5. A towel cabinet having a feed roll in its upper portion, an opening below said feed roll and a trough like support below the opening, said support having a concave upper and inner surface and openings through its bottom, a shaft below said support and having feed rolls projecting into said openings, said shaft being geared to said first mentioned feed roll. 110

In witness whereof, I have hereunto set my hand this 10th day of January, 1927.

FRANK M. STEINER.
